CLAIM

The ornamental design for a battery connector or the like, as shown and described.

DESCRIPTION

FIG. 1 is a top perspective view of a battery connector or the like showing my new design;

FIG. 2 is a top perspective view thereof at a different position;

FIG. 3 is a bottom perspective view thereof;

FIG. 4 is an exploded perspective view thereof;

FIGS. 5, 6, 7 are respectively a right side elevational view, an end elevational view of the top half of the connector, or the like, the bottom half being omitted for purposes of disclosure;

FIGS. 8, 9 and 10 are respectively a right side elevational view, a bottom plan view and an end elevational view of the bottom half of the connector, or the like, the top half being omitted for purposes of disclosure.

FIG. 1.FIG. 3.

FIG. 4.

FIG. 6.

FIG. 7.

FIG. 5.

FIG. 10.

FIG. 8.

FIG. 9.
